UNITED STATES PATENT OFFICE.

FLOYD A. SCOTT, OF SOMERS POINT, NEW JERSEY.

PASTE TUBE.

Application filed March 11, 1927. Serial No. 174,591.

This invention relates to a tube for holding paste and the like, the general object of the invention being to provide means for facilitating the ejection of the material from the tube, by means of a follower arranged in the tube and actuated by means of a threaded shaft which is rotated by a knurled disk arranged at the rear end of the tube.

Another object of the invention is to provide means for holding the tube against a wall or the like in such a manner that the ejecting means can be operated to eject some of the material from the tube without necessitating the removal of the tube from the holder.

A further object of the invention is to provide means for indicating when the tube is empty.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation showing a number of tubes supported in a holder.

Figure 2 is a top plan view of Figure 1.

Figure 3 is an enlarged longitudinal sectional view through a tube.

Figure 4 is a fragmentary view showing the means for indicating when the tube is empty.

Figure 5 is a section on line 5—5 of Figure 3.

Figure 6 is a view of the nut member or follower.

In these views, 1 indicates the tube for holding the paste or other material, this tube being formed in the usual manner, except that instead of folding the rear end upon itself, I close said rear end by a circular block or member 2 which is formed with an annular groove therein so that a portion of the tube can be crimped to the block, as shown at 3. A gasket 4 of suitable material is placed between the block and tube to insure a tight joint. This block has a hole in its center through which passes the unthreaded portion of a screw shaft 6, the

outer end of which carries a knurled disk 7 which forms a handle whereby the shaft can be rotated. Washers 8 are placed on the shaft, one on each side of the block and a nut 9 on the shaft holds the parts together. A follower or nut member 10 engages the threaded portion of the shaft and said member has a notch 11 therein which engages a longitudinally extending bead 12 formed in the tube by grooving the same exteriorly.

Thus by turning the shaft, the member 10 will be fed toward the outlet end of the tube, due to its engagement with the threaded portion of the shaft and also due to the fact that it is held against rotation by the bead engaging the notch 11, so that the material will be forced from the mouth of the tube.

When the follower nears the front end of the tube, it will engage a pin 13 mounted in said front end and project the same, thus indicating that the tube is empty.

I also provide a holder 14 for supporting a number of tubes on a wall or other support, said holder having semi-circular grooves 15 therein, each of which is adapted to frictionally hold a tube. The bottom of each groove has a seat 16 thereon for entering the groove in the tube formed by the bead 12, so that the tube is held against rotation in the holder when the shaft is turned to eject some of the material from the tube.

This holder, as will be seen, will support the tube in such a manner that the material can be ejected therefrom on to a brush or the like without necessitating the tube being taken from the support, it being understood that the tube is placed in the holder with its outlet end lowermost.

From the foregoing it will be seen that I have provided simple means for facilitating the ejection of material from a tube and without handling the tube or taking it from its support, so that toothpaste, for instance, can be easily and quickly applied to a brush.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A tube of the class described having a closure in its rear end, a screw shaft having

an unthreaded portion rotatably mounted in the closure with a threaded portion located in the tube, a follower in the tube having a threaded hole therein engaged by the shaft, means for preventing rotary movement of the follower, a handle member on the outer end of the shaft and a pin in the front end of the tube and adapted to be projected by the follower when the follower nears the end 10 of the tube, for indicating that the tube is empty.

2. In a dispensing device of the character described, a tube having a constricted charge end, a block member secured within the other

end of the tube, a shaft having a smooth portion rotatably engaged axially thru said block, a head carried by said shaft above and of the same diameter as the tube for effecting rotation of the shaft, a follower slidably and non-rotatably mounted within the tube and having threaded engagement with the threaded portion of the shaft, and means mounted at the discharge end of the tube and positioned in the path of travel of the follower and projectable thereby for indicating approximate emptiness of the tube. 15 20 25

In testimony whereof I affix my signature.

FLOYD A. SCOTT.
